COUNTERBORING TOOL

Oscar C. Hedin, Minneapolis, Minn., assignor to
The Weldon Tool Company, Cleveland, Ohio, a
corporation of Ohio

Application October 10, 1939, Serial No. 298,836

9 Claims. (Cl. 77—66)

This invention relates to improvements in pilots for metal cutting tools with which a pilot is or can be used, particularly tools of the counter-cutting type, such as reamers and counterbores.

5 The invention has found valuable application in a tool of the counterbore type.

Objects of the invention are: To so detachably mount the pilot that pilots of different diameters can be quickly substituted, and to provide a 10 character of mount which cannot become loosened in use and which will prevent such movements of the pilot as will mar or dull the cutting ends of the tool, or as will allow the pilot to assume eccentric positions.

15 I am aware that various attempts have been made to provide removable pilots but, insofar as I know, there exists no detachable pilot which is entirely satisfactory.

In some cases the pilot has been made removable by providing it with a small shank 20 which is inserted in an opening in the stem of the tool, wherein it is locked by a set screw. When such a pilot is in operative position the rear or inner end of the pilot bears against the ends of 25 the cutting lips. This type of pilot becomes loose and vibrates or chatters, and the inner end surface of the pilot can chew up or mar or deface the cutting lips. When this marring occurs during use of a larger size pilot, and one wishes to 30 use the tool with a smaller size pilot, it is found that the cutting tool has been so chewed up or marred that it is necessary to re-sharpen the same. This takes time and needlessly shortens the life of the cutting part of the tool. Insofar 35 as I am aware, in all of the manufacturing tools which have had detachable pilots, it has been necessary to use set screws or the like for holding them in place. The main objection is that those pilots work loose, with the results above mentioned. The ideal pilot must be rigid, and I 40 have provided this rigidity in a detachable pilot.

An important feature of my invention consists in providing a mount for the pilot which is of one piece with the tool, that is, integral therewith. 45 The mount is of one piece or integral with the stem, as distinguished from being separable therefrom. Another feature is the provision of a tapered mount not necessarily of one piece, with the tool.

50 In my invention I turn a tapered extension at the end of the tool which tapers convergently in boring direction, and then I form a corresponding tapered opening in the pilot. Each pilot of a series of pilots has a different outer diameter but 55 has the same diameter or dimension of taper, so

that each one will fit one and the same integral tapered extension.

Features of the invention include: the use of a pilot-mounting extension which is of one piece with the tool; the use of a tapered mount, whereon the pilot is frictionally held so that it can be loosened by a slight tap; the use of a cylindrical mount of one piece with the tool; the use of screw threads to secure the pilot to a mount which is integral with the tool; the scheme of the substitution of pilots of different diameters on one and the same amount; and all details of construction shown.

Objects, features and advantages of the invention will be set forth in the specification and 15 drawing, forming a part of this application, and in said drawing;

Figure 1 is an elevation of a counterbore tool showing my invention applied thereto and showing the tool in counterboring position in relation 20 to the work;

Figure 2 is an enlarged section of the lower part of the tool with my invention applied thereto;

Figures 3, 4 and 5 are sections, respectively, of 25 pilots of different outside diameters, any one of which pilots can be applied to one and the same pilot mount of this invention;

Figure 6 is an enlarged section of a modification showing the pilot attached by screw threads; 30

Figure 7 is a section of another modification showing the pilot held on a cylindrical mount; and

Figure 8 is an axial section of a centering or 35 sharpening pilot.

Referring first to Figure 1, I have illustrated my invention as applied to a counterbore tool having two lips only, but it will be understood that the invention may be applied to any tool on which a pilot can be used or is needed, to provide means whereby a detachable pilot is unfailingly rigidly centered for performing its function and yet is quickly and easily removable so that pilots of other outside diameters can be substituted on one and the same mount.

The numeral 1 indicates the shank of the tool and the numeral 2 indicate the cutting lips. Numerals 3 indicate the cutting edges of the lips. At the upper end of the tool is a centering depression 5 corresponding to a similar depression 50 at the opposite end of the tool, as hereinafter described. By means of these depressions the tool can again be supported for operations which will be later described.

Referring now to Figure 2, a salient feature of 55

my invention is the provision of a pilot support or extension which is of one piece with the stem 1, and which is turned and/or ground as the stem is turned and/or ground so that perfect centering can be accomplished. This extension is generally indicated by the numeral 10 and it is noted that it is tapered convergently in boring direction. The pilot element per se is indicated at 11 and has a correspondingly tapered opening 10 which has an accurate fit with said projection so that good frictional contact is obtained, which alone secures the pilot in position on the projection or extension 10. It is desirable to have the inner end or surface 12 of the pilot 11 spaced 15 from the cutting edges 13 of the lips 2, and it is desirable to always maintain this relation after sharpening of the lips has occurred, which operation shortens the lips in an axial direction (see dot-and-dash lines 13' roughly indicating the position of the cutting edges after sharpening). If it is desired to maintain the predetermined special relation between the face 12 and edges 13, the mount element is also ground, and so that the same taper is maintained. For this purpose the 20 tool is centered in the grinder by means of the centers 5 and 14.

Figures 3, 4 and 5 show sectional views of pilots of different diameters, said diameters being respectively indicated by the letters A, B, C. In 30 these figures it will be noted that the internal diameter of the conical opening indicated at D remains the same as the diameter D' (see Figure 2) of the tapered projection 10. The result is that either of the pilots respectively indicated at 16, 35 17, 18 can be frictionally, immovably, rigidly held on the projection 10 of Figure 2. For ease of manufacture, of course, it might be considered most convenient to make the pilot extension cylindrical, and Figure 7 shows such construction.

40 The important feature is the making of the pilot extension 10 or its equivalent, of one piece with the stem 1 to assure rigidity, and so that the mount can be machined with the stem and can be re-ground to maintain the proper relations between a pilot mounted upon it, and the cutting edges of the tool as the cutting edges are sharpened back in an axial direction.

To further define the meaning of the expression "of one piece with," as used to describe the 50 character of the extension upon which the pilot is mounted, it may be said that the most practicable way to form the extension is by turning during manufacture. However, if the tool is cast, then of course the extension should be formed by 55 casting and would be of one piece with the shank. It is conceivable that the extension might be welded in place, and if it were this would be another way of obtaining a rigid, non-removable support for the pilot. These ways of obtaining 60 this rigidity are mentioned to make clearer the meaning of the terms "of one piece with" or "integral."

By making this tapered extension of one piece with the shank or with the tool a rigid mount is 65 obtained. This tapered extension may be called a sub-pilot, and upon this sub-pilot can be driven a master pilot of the desired outside diameter, this master pilot having, as before mentioned, a tapered hole which permits it being driven into 70 frictional engagement with the sub-pilot or tapered extension. Thus, there is here combined all the virtues of the solid type of counterbore with the advantage of interchangeability of pilots. As an extreme example, consider several 75 screws, all of which have heads one inch in di-

ameter but in each of which the shank has a diameter differing from that of the other, for example, ranging in diameter from $\frac{5}{8}$ ths to $1\frac{1}{16}$ ths of an inch. To do counterboring for the heads of these screws whose shanks vary in diameter there would ordinarily be required as many counterbores with solid or integral pilots as there are different diameters of screws. Thus, it can be seen what advantages accrue from having a counterbore with interchangeable or replaceable 10 pilots.

My invention gives a construction which has a maximum strength and rigidity and more nearly approaches the solid type pilot than any other device known to me. 15

By the scheme herein or method of manufacture constant concentricity of pilot and counterbore diameter is assured. The taper of the sub-pilot is ground at one and the same time as the outside diameter of the counterbore proper. 20 The master pilots are easily made accurately, with their outside diameter concentric with the axis of the tool. It is to be noted that lack of concentricity between pilot diameter and cutting-lip diameter is the most frequent cause of 25 pilot breakage.

Another advantage of the present invention resides in the fact that the taper can be ground so as to follow back as the cutting ends of the lips are ground farther and farther back from their position when the tool is new. As the lips are ground back in sharpening, the tapered extension can also correspondingly be ground back so that the inner end of the pilot, that is, the end which is nearest the lips, can always be made to 35 assume a desired predetermined spaced or other relation with the cutting lips. However, by the use of this invention, even though the inner end of the pilot were against the cutting lips, there would be no chattering with marring or dulling 40 of the tool, because there is positively no relative movement of the pilot.

In Figure 6 I have shown a modification in which the sub-pilot or pilot mount or projection is threaded as at 20, and the pilot 21 is correspondingly threaded. In this case two methods may be employed for threading the sub-pilot: (a) the threads may be cut before the tool is hardened, or (b) the threads may be ground thereon after hardening. Then as the cutting lips are 50 sharpened back, the pilot is simply screwed on farther.

In Figure 7 I have shown a modification in which the sub-pilot or mount 24 is cylindrical, rather than tapered. In this case the master pilot or part 25 has a slightly under-sized hole and the pilot 25 is either pressed or shrunk, or has a driven fit with the extension. In this case, as the cutting lips are sharpened back, means 60 must be so exerted as to permit proper spacing between the elements.

Although the greatest number of advantages of this invention accrue from having the mounting extension for the pilot of one piece with the tool, I believe I am also the first to provide a sub-pilot which is integrally attached to the tool and which has a surface which convergently tapers in a direction away from the end of the tool and on which tapering surface a pilot is secured frictionally, so that all that is necessary to remove the pilot is to lightly tap that end of it which is nearest the cutting lips of the tool. The feature can be used with or without having the pilot mount or sub-pilot of one piece with the 70 tool. 75

This invention, therefore, provides the feature of interchangeability from a minimum size compatible with strength, to a maximum size, such that the pilot may be a few thousandths of an inch smaller than the diameter of the cutting lips, in which case the counterbore has become a reamer for the accurate finishing of the hole to its final size, which feature and/or function is a valuable one.

10 The type of support herein is very easy to manufacture and therefore much cheaper to manufacture because there is no extra drilling or fitting or threading for setscrews, as in previous devices.

My sub-pilot or tapered extension can be made

15 very hard, and it is only submitted to such compression as results from driving on the master pilot. However, the strength of the master pilot is assured by the fact that it is surface-hardened only, and has a tough and stronger core under 20 the hard surface, which gives it sufficient strength to withstand being driven onto the sub-pilot, and the necessary amount of flexibility to permit it to strongly, frictionally engage when driven onto the sub-pilot. At the same time being tapered 25 it is readily driven off or removed from the sub-pilot by a light, snappy blow with a hammer and/or screw driver.

As before explained, because of various manufacturing requirements, the same maximum diameter of counterbore portion or lips is often required for a variety of screw holes of different sizes. For example, consider several screws, all having heads one inch in diameter, but each having a shank of a different diameter ranging from 35 $\frac{5}{8}$ of an inch to $\frac{1}{8}$ of an inch. It will be seen that for the same diameter or cutting area represented by the letter E in Figure 2, any one of the pilots 16, 17 and 18 can be substituted on mount 10. The dimension E corresponds in the 40 example to a head which is one inch in diameter and the elements 16, 17 and 18 correspond to shank sizes ranging from $\frac{5}{8}$ of an inch to $\frac{1}{8}$ of an inch.

The present invention can be applied to any 45 tool which uses a pilot. For example, it can be used in or for a spot-facing tool. The principal difference between counterboring and spot-facing involves dimensions and proportions. Counterboring provides a recess which receives generally the entire head of a screw. Spot-facing provides, in relation to a bored hole, a circular, flat area concentric with and surrounding the hole at the surface. Generally the diameter of the 50 area is proportionately much greater than that of the diameter of the hole, and is of very shallow depth. The spot-facing tool has cutting lips and a pilot, and this invention assures that the spot-faced area will be concentric with the hole, and also that the flat area will be in a plane at right 55 angles to the axis of the hole. In the case of a part to which a smaller part is to be bolted, the hole is drilled for the screw and this drilling operation is followed by spot-facing, thus providing a flat supporting area. By the same procedure, and more frequently, a flat surface is provided 60 on which the head of a cap screw may rest, and in this case the screw is entirely above the surface. Usually in counterboring the screw head becomes flush with or below the surface.

70 This invention may also be applied to a reamer. The drilled or bored hole is reamed and the reamer removes but a slight amount of material. The hole may be a few thousandths of an inch out of round and the reamer will correct this 75 condition, or the hole may be a few thousandths

of an inch undersize and can be corrected by a reamer, using the invention. Reaming is generally done throughout the length of the hole, that is, all the way through the material. For example, if a truly round, straight and accurate 5 hole is required to be finished to .5000 of an inch, the initial operation would be to drill and/or to bore the hole to a diameter of a few thousandths less than .5000 of an inch. Then with a reamer having a cutting lip diameter of .5000 of an inch, 10 and with a pilot of my invention having a diameter corresponding to the original hole, my tool is run through the hole and reaming action is performed.

The invention herein results in a very simple, 15 easily manufactured, fool-proof, accurate and strong counterbore mounting, and while I claim specifically the tapering counterbore mount, I believe that the invention is broader than the specific shape of the mount and believe that I 20 am the first to conceive of making this extension or mount integral or of one piece with the shank or tool, thereby obtaining positive rigidity and assuring concentricity between the pilot and cutting-lip diameter. The master pilots can be 25 easily and accurately made and so made as to be positively held only by friction, but easily and quickly removable.

It is to be noted that in order to resharpen the cutting lips, as well as to sharpen the same at 30 the time of manufacture, the tool is supported by the work-supporting centers of a grinding machine that engage the centers 5 and 14. Inasmuch as the lips will be subjected to many resharpenings, and inasmuch as it is desired to 35 maintain the special relation between the end of the pilot and the cutting lips, it is also necessary to cause the taper to follow back by re-grinding in correspondence to the sharpening back of the lips. After this re-grinding operation, the outer 40 end of the sub-pilot is ground off or cut off so that it will not protrude beyond the outer end of the master or control pilot. After this cutting-off operation has occurred a sufficient number of times, the centering opening 14 disappears, and 45 it is therefore necessary to apply the device shown in Figure 8 which I call a centering pilot. This device merely has a taper which fits the taper of the sub-pilot, and has a centering depression 28 which, in conjunction with depression 50 5, allows the proper centering in a machine. This centering or sharpening pilot can be driven onto the taper.

The wedging, attaching action of the pilot 55 mount is a valuable feature. By making the mount tapered, the pilot, by its circumscribing, constricting and wedging action, serves to reinforce the mount, and to provide the much desired immobility of the pilot when the tool is being used.

I claim as my invention:

1. A tool of the counter-cutting type having 65 extending beyond its boring end a projection which is of one piece with the tool, and a pilot element removably mounted on said projection by means of a tapering friction fit which permits said pilot to be loosened and removed by a blow applied against that end of it which is nearest the boring end of the tool.

2. A tool of the counter cutting type having 70 extending beyond its boring end, a projection which is of one piece with the tool, said projection being convergently tapered in the direction away from said end, and a pilot element removably mounted on said projection and operatively 75

held thereon only by the frictional engagement with said projection.

3. A tool of the counter-cutting type having cutting lips and having at a point beyond said lips at its boring end, an axial projection which is of one piece with the tool, said projection being convergently tapered in the boring direction of the tool, and a pilot element mounted on and having an accurate tapering fit with said projection, said pilot element being held only by the frictional engagement of a tapering surface with the tapering surface of the projection.

4. A tool of the counter-cutting type having extending beyond its boring end an extension which is of one piece with the tool and a pilot removably mounted on said extension and secured thereon only by frictional engagement of surfaces of said pilot and projection and so that said frictional securing action can be annulled by moving said pilot axially.

5. A tool of the counter-cutting type, having a stem having cutting lips adapted to be sharpened by grinding in an axial direction and away from the boring end of the tool, said stem having of one piece therewith and at a point immediately adjacent the cutting ends of said lips a pilot-mounting extension, and a pilot removably mounted on said extension and rigidly secured thereon only by frictional action, said pilot having its inner end occupying a predetermined position with respect to the cutting ends of said lips, whereby as the lips are ground in an axial direction to sharpen them, the extension can also be correspondingly ground axially in order that the inner end of the pilot shall always occupy said

predetermined relation to said lips after sharpening of the same.

6. A counterboring tool having, extending beyond its cutting end and of one piece with the shank of the tool, an outwardly convergently tapered pilot mount adapted to receive and wedgingly detachably cooperate with a correspondingly tapered opening of a pilot element.

7. A one-piece counterbore having cutting portions which face and cut in an axial direction only, and having extending beyond those cutting portions a pilot-mounting projection which is of one piece with the tool, and a pilot element as a separate piece removably but rigidly mounted on said projection.

8. A one-piece counterbore having cutting portions which face and cut in an axial direction only, and having extending beyond those cutting portions a pilot-mounting projection which is of one piece with the tool, and a pilot element as a separate piece removably but rigidly mounted on said projection, said pilot having its inner end adjacent but spaced from said cutting portions in an axial direction.

9. A one-piece tool of the counter-cutting type having a stem and cutter elements extending radially beyond the stem and extending longitudinally of the stem and having cutters which face and cut only in an axial direction, said tool having extending beyond said cutters a pilot mounting projection which is of one piece with the tool and a pilot element as a separate piece removably but rigidly mounted on said projection.

OSCAR C. HEDIN. 35
